UNITED STATES PATENT OFFICE.

ALBERT HUET, OF LOIGNIES, BELGIUM, ASSIGNOR TO ATELIERS DE CONSTRUCTIONS ELECTRIQUES DE CHARLEROI SOCIETE ANONYME, OF BRUSSELS, BELGIUM.

ELECTRIC TRANSFORMER.

Application filed January 4, 1928, Serial No. 244,457, and in Belgium January 4, 1927.

This invention relates to the construction of electric transformers.

An apparatus for welding by means of the electric arc must present the following electrical characteristics:

(1) A fairly high voltage on open circuit, generally from 65 to 90 volts, in order to allow the striking of the arc.

(2) A heavy drop of voltage on load, in such a way that the voltage at the terminals of the output or external circuit shall be reduced to a value lying between 20 and 30 volts, this value corresponding to the fall of potential in the arc.

(3) The possibility of regulating the load current according to the quality of the electrodes employed and to the mass of the parts to be welded.

These conditions are generally realized by means:

(a) of a group constituted by a transformer and a variable inductance placed in series with the secondary of the transformer. The transformer may have a heavy voltage drop, the inductance acting simply to limit the load current.

(b) of a transformer provided with a magnetic shunt having an adjustable air gap allowing variation of the voltage drop.

The present invention has for its object the construction of a transformer with variable drop of voltage, applicable in particular to electric welding and comprising for the purpose of voltage-drop variation neither an external inductance nor a magnetic shunt. The transformer, according to the present invention, is provided, in addition to the primary and secondary windings, with a supplementary winding, hereinafter referred to as the tertiary winding, which is arranged in such a way as to embrace practically only the dispersion flux of the transformer or a part of said flux.

The connection of this tertiary winding in series with one of the other windings, either the primary or the secondary, allows of regulating the value of the voltage-drop of the transformer, as will be explained hereafter.

Upon the accompanying drawings, to which reference will be made in the following description, the same reference letters and numerals designate the same elements or parts. On these drawings, Figures 1, 3, 5 and 7 represent diagrammatically, by way

of example, two different arrangements of a single phase transformer in accordance with the invention, having a heavy voltage-drop and with a single undivided magnetic circuit.

Figures 2, 4, 6 and 8 are sections taken along the line M—N of Figures 1, 3, 5 and 7 respectively.

Figures 9 and 12 represent diagrammatically, by way of example, two arrangements of transformer in accordance with the invention, for converting three-phase current supply into single phase current for welding purposes.

Figures 10 and 13 are sections taken along the line M—N of Figures 9 and 12 respectively.

Figure 11 is an explanatory diagram.

In the forms of construction shown in Figures 1 to 4, the primary winding 1 is wound entirely upon the core 11 and the secondary winding 2 upon the core 12; it is desirable to make it clear that this arrangement is not indispensable. The tertiary winding 3, having the regulating or control tappings, is simply wound around the two cores 11 and 12, as can be seen particularly in Figure 2. This tertiary winding 3 is connected in series with the secondary winding 2, in such a way that the current circulates therein in the same direction as in the secondary (as indicated by the arrows in Figures 1 and 2) or else in such a way that the current circulates therein in the contrary direction (as represented diagrammatically in Figures 3 and 4).

Control tappings *a b c . . .* are connected at various points of the tertiary winding 3.

The feed to the primary winding 1 is effected at the points A and B. The output circuit is connected to the point A' and to one of the points or tappings B' *a b c . . . p* for low currents (Figures 1 and 2), or to the point A' and to one of the points or tappings B' *c b a . . . q* for heavy currents (Figures 3 and 4).

In view of the fact that the resultant flux embraced by the tertiary winding 3 is very weak on open circuit, the voltage at the terminals of the secondary winding 2, when the output is nil, varies very little whatever be the number of tertiary coils in service; this condition is necessary in order to obtain an easy and regular striking of the electric arc.

On load, on the other hand, the tertiary

winding is traversed by the leakage or dispersion flux of the primary winding 1 and of the secondary winding 2 of the transformer.

- 5 In the example described above, with reference to Figures 1 to 4, the tertiary winding 3 is simply wound around the two cores 11 and 12. An identical result would be obtained by placing this winding 3 in any other 10 manner such that it embraced the dispersion flux of the transformer, wholly or in part.

The tertiary winding 3, instead of being single, may be constituted, for example, by two series of windings respectively wound 15 around the cores 11 and 12, as represented in Figures 5 to 8.

Figures 5 and 6 represent the transformer arranged in this manner, with current circulating in the tertiary winding 3 in the 20 same direction as in the secondary 2.

Figures 7 and 8 represent the same transformer, with current circulating in the tertiary winding 3 in the direction opposite to the circulation of the current in the 25 secondary 2.

The windings are connected in such a way that on open circuit the electromotive forces generated in each portion of the tertiary winding are practically equal and opposite.

30 Connection is then effected as for the single winding and as represented respectively in Figures 5, 6 and 7, 8.

The input to the primary winding 1 is effected at the points A and B. The output 35 circuit is connected to the point A' and to one of the terminals or tappings B' a b p for low currents (Figures 5 and 6) or to the point A' and to one of the terminals or tappings B' b a q for heavy currents (Figures 40 7 and 8).

It may here be pointed out that the arrangement represented in Figures 5 to 8 comprises only three groups of windings and therefore allows the utilization of only two 45 intermediate regulating or control tappings a b.

I have described above a single-phase transformer having variable drop of voltage, applicable in particular to electric welding and comprising for the purpose of voltage-drop regulation neither an external inductance nor a magnetic shunt, the variable voltage-drop transformer being provided in addition to the primary and secondary windings with a supplementary or tertiary winding arranged in such a way as to embrace practically only the dispersion flux of the transformer or a part thereof, and the connection of this tertiary winding in series 55 with the secondary allowing of regulating the value of the drop of voltage and therefore the welding current.

When the outside supply is of three-phase 60 current, the transformer apparatus according to the present invention can be connected

between two phases of the three-phase system, or again in order to obtain a more favourable distribution of the current in the various phases of the supply, there may be employed two single-phase transformers of 70 which the primaries are coupled in V, while the secondary and tertiary windings of each apparatus are connected in series.

However, it is of greater advantage in such case to construct an improved apparatus arranged according to the principle stated above but modified as described below.

Referring to Figures 9 to 13 of the accompanying drawings, the three cores of the transformer are numbered 11, 12 and 13, two 80 of these cores, which may be selected arbitrarily, each supporting a primary winding 1, 3.

For the sake of symmetry, the cores 11 and 13 are adapted in the diagram to receive the 85 primary windings 1 and 3; this arrangement however is not indispensable. These primaries 1 and 3 are then coupled by the well known V-connection system and connected by the three terminals A, B and C to the 90 three phases of the three-phase net work (Figures 9 and 12).

According to a well understood construction, the coupling will be carried out in such a way that the fluxes Φ_1 and Φ_3 generated in the cores 11 and 13 will be dephased by an angle of 60° . Thus the fluxes combine as indicated in Figure 11, and the core 12 is traversed by a resultant flux Φ_2 equal to $\sqrt{3}$ times the flux Φ_1 or Φ_3 passing through one 100 of the cores 11 or 13. The secondary winding 2 is then wound wholly around the core 12.

The transformer arranged in this manner 105 presents a considerable dispersion flux when it is on load, and there is therefore a heavy voltage-drop on load. It is to be noted that this dispersion flux is in phase with the output current.

In order to obtain the desired regulation, as in the case of a single-phase transformer, there is connected in series with the secondary a tertiary regulating winding which embraces the dispersion flux wholly or in part. This tertiary winding 4 might for example be wound around the three cores as indicated in Figures 9, 10, 12 and 13; it is then connected in series with the secondary winding 2 in such a way that the current circulates therein in the same direction as in the secondary, as indicated by the arrows in Figures 9 and 10, or else in such a way that the current circulates therein in the contrary direction, as indicated by the arrows in Figures 11 and 13.

Regulating tappings a b c . . . are connected to various points of the tertiary winding 4.

When the primary supply is fed in at A, 130 B and C, the output circuit is connected to

the point A' and to one of the tappings B' a b c . . . p for weak currents (Figures 9 and 10) or to the point A' and to one of the tappings B' c b a . . . q for heavy currents (Figures 12 and 13).

In order to obtain the desired regulation of the voltage-drop, the tertiary winding or a part thereof may be connected either in conjunction with or in opposition to the secondary winding, as has been explained above.

It is also to be noted that it is permissible, without exceeding the scope of the invention, to obtain the regulation of the load current by connecting the tertiary winding in series 15 with the primary, instead of connecting it with the secondary as has been described with reference to Figures 1 to 6.

The advantages presented by the transformer according to the invention, as compared with transformers of the ordinary kind are the following:—

- (1) Lightness;
- (2) Reduced overall size;
- (3) Higher output due to the fact that 25 the magnetic circuit is undivided;
- (4) Great simplicity of construction;
- (5) Very economical design.

What I claim is:—

1. An electric welding transformer, comprising a magnetic core, primary and secondary windings upon separate limbs of said core, and a supplementary winding embracing a plurality of core-limbs carrying said first mentioned windings.
2. An electric welding transformer, comprising a magnetic core, primary and secondary windings upon separate limbs of said core, and a supplementary regulating winding embracing a plurality of core-limbs carrying said first mentioned windings.

40

ings, said regulating winding being arranged to be traversed on open circuit by a resultant magnetic flux of practically nil value and on load by the dispersion flux of said first-mentioned windings.

45

3. An electric welding transformer, comprising a magnetic core, primary and secondary windings upon separate limbs of said core, and a supplementary winding adapted to be connected in series with one 50 of said first-mentioned windings, said supplementary winding being wound directly over and upon the same core-limbs as one of said first-mentioned windings.

55

4. An electric welding transformer, comprising a magnetic core, primary and secondary windings wound upon limbs of said core, a tertiary regulating winding, said regulating winding embracing a plurality of core-limbs carrying said first-mentioned 60 windings, and means for connecting said regulating winding in reversible series with one of said first-mentioned windings.

65

5. An electric welding transformer, comprising a magnetic core, primary and secondary windings upon separate limbs of said core, a tertiary regulating winding wound to give variable taps, said regulating winding embracing the same limbs of said magnetic core as one of said first-mentioned 70 windings and being traversed on load by the dispersion flux leaking between said first-mentioned windings, and reversible means for connecting one of said first-mentioned windings in series with the variable taps of 75 said regulating winding.

In testimony whereof I hereunto affix my signature.

ALBERT HUET.
